CLAIM

The ornamental design for a grip for television camera lens, as shown and described.

DESCRIPTION

FIG. 1 is a top, front and left side perspective view of a grip for television camera lens showing my new design;

FIG. 2 is a top, front and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a reduced top, front and right side perspective view showing the grip being attached to a television camera lens.

The broken line portion depicting a camera lens in FIG. 9 is shown to illustrate environment only and form no part of the claimed design.
